BURT BECKER

Parker Cook Attorney

UNITED STATES PATENT OFFICE

BURT BECKER, OF PHILADELPHIA, PENNSYLVANIA

REBOUNDING HAMMER

Application filed September 18, 1930. Serial No. 482,821.

My invention relates to new and useful improvements in shot guns, and more particularly to the hammer mechanism therefor.

One of the objects of the present invention is to provide a shot gun, of either single or double barrel type, wherein, as a trigger is pulled, the hammer will not only strike the primer of the shell to fire the same, but it will slightly rebound, so that its nose or firing point will not remain protruded through the plunger hole.

As is well known to those skilled in the art, or to those familiar with firearms, there is always provided, either a firing pin, or a hammer with a nose or firing pin formed integrally therewith, and those hammers that have the firing pin integral with the hammer, or even those that have a separate firing pin, often cause inconvenience to the shooter, for the reason that after the gun is fired, these firing pins, either the integral or separate type, remain protruded in the plunger hole so that the gun does not break open easily. This happens because the nose of the firing pin or nose of the hammer remains embedded within the primer.

Still another object of the invention, therefore, is to provide a shot gun wherein the hammer or hammers are provided with an integral firing point or nose, and wherein, when a hammer is released, its nose will strike the primer of the shell and the hammer rebound, so that the nose will not project through the plunger hole, thus assuring an easy breaking or opening of the gun at all times.

Still another object of the invention is to provide a shot gun with a rebounding hammer, and wherein the hammer spring not only applies the striking force to the hammer, but is also utilized to cause the rebounding action of the hammer.

Still another object of the invention is to provide a shot gun with a rebounding hammer, wherein it is necessary only to provide an additional dog carried by the hammer, so that the hammer spring acting on the dog will permit, or rather cause, the hammer to slightly rebound immediately after striking the primer.

Still another object of the invention is to

provide a shot gun which, of course, if of the double barrel type, will have two rebounding hammers and if of the single type, will have one rebounding hammer.

At the outset, it might be mentioned that the rebounding hammer, as will be explained, is especially adaptable to the "Fox" type of gun, which type is well known to those familiar with shot guns.

Still another object of the invention is to provide a shot gun with rebounding hammers, so that there is never any chance of the gun going off as the gun is closed, which occurrence is not unusual in the ordinary type of gun, as should the firing pin or nose of the hammer protrude through the plunger hole as the gun is closed, it is apt to often strike the primer, and thus cause the premature firing of the gun.

With these and other objects in view, the invention consists in certain new and novel arrangements as will be hereinafter more fully described and pointed out in the claims.

Referring now to the drawings showing a preferred embodiment of the invention,

Fig. 1 is a fragmentary side elevation, partly in section, showing the rebounding hammer in its rebounded position, the dotted lines showing the striking position, a number of parts being omitted for the sake of clearness;

Fig. 2 is a similar view, showing the gun in a broken position and the hammer cocked;

Fig. 3 is a fragmentary sectional view, showing a hammer of the far barrel as having been fired and having rebounded to its normal position;

Fig. 4 is a fragmentary bottom plan view with the trigger removed;

Fig. 5 is a detailed side view of the hammer;

Fig. 5-A is a similar face or front view of the same;

Fig. 5-B is a top plan of the hammer, its dog being shown in dotted lines.

It will be understood at the outset that I have illustrated the invention as used with a double barrel shot gun, although the invention might equally as well be applied to the single type gun.

It also might be mentioned at this time, that I have not shown or described the locking mechanism for the gun, nor have I illustrated the safety device or the ejectors, as 5 they form no part of the present invention, and may be of any type desired.

As may be seen in Fig. 1, there is shown a fragmentary portion 1 of a fore-end, a part 10 of one of the barrels, in which there is a shell 3. There may also be seen a portion of the box frame 4, which fits on a stock (not shown), there being the upper tang 5 and the locking lever 6. In the under portion of the frame may be seen the plate 7, which carries 15 the trigger mechanism and whose rear end forms a tang 8. The barrels are, of course, pivoted on the pin 9, and there may be seen the usual cocking slide 10 which will be forced rearwardly by the lug 11 when the gun 20 is opened, as may be seen in Fig. 2.

The parts so far enumerated are common to various types of shot guns, and need not be described more in detail.

Now still referring to Fig. 1, there will be 25 seen mounted within the frame 4 a novel form of hammer 12, which is pivotally mounted on the pin 13, which pin extends through the opposite sides of the frame 4. Of course, in a double barrel shot gun, two of these hammers are used, as may be seen in Fig. 4, and a description of the one is a description of both.

Now before describing more in detail the hammer, there will be noticed a sear 14 pivoted as at 15 to engage the firing notch 16 of the hammer, this sear, of course, being tripped by the trigger 17, as may be seen in Fig. 1.

I have not shown a safety lock on the tang 5, nor have I shown the locking bolt for the 40 gun, nor the ejectors, but it will be understood that any desired type may be used, as the present invention relates to the rebounding hammers and their operation.

Now mounted in the forward end of the 45 frame and referring to Figs. 1 and 2, there will be noticed the hammer spring 18, which fits within its chamber 19, while bearing against the spring is the little follower 20, which has the conical recess 21 formed there- 50 in. Likewise, it will be understood that there will be one of these cocking springs, and followers, for each of the hammers in a double barrel gun.

Still referring to Fig. 1, there will be seen 55 the plunger hole 22 in the plate 22', through which will pass the integral nose or firing pin 23 of the hammer 12.

Now referring more specifically to the hammer as shown in Figs. 5 to 5-B inclusive, 60 this hammer is of irregular shape, having the upper portion 24 which is widened as at 25 to provide the necessary weight, and is then narrowed as at 26, there being a second hole 27' extending through the hammer. It is to be 65 noticed that the hammer is slotted as at 28, so

that the hole 27' will pass through the opposite side walls of the slot. The hammer is then offset, as at 29, and is provided with the nose 30, which nose will be engaged by the cocking slide 10 when the said slide is forced 70 slightly rearwardly when the gun is opened to cock the same. Now where two hammers are used, one is a right and the other a left, so that they may be properly nested. (See Fig. 4.)

Now pivotally mounted within this slot 28 is the little dog 31 with its opening 32 so that this dog may be held by a pin 33 passed through the opening 27' in the hammer. This little dog has the little round pointed 80 nose 31', is cut away in its enlarged rear as at 34 to partly encircle the pin 13 and rest against it when the hammer is in its extreme forwardmost position. The dog is slightly pointed as at 34'. Now the rear portion of 85 the dog, that is, the pointed portion 34' will contact with the rear wall of the slot 28 in the hammer just below the pin 13 when the hammer is released, as shown in Fig. 1 of the drawings, to cause the same to rebound.

In Fig. 3 I have shown the far hammer 12' for clearness of illustration, and its sear 14'. Likewise the cocking slide 10 and its cooperating spring 35 may be seen, and it will be understood that this cocking slide and spring 95 are placed centrally of the tubes or barrels, and the frame 4, so that when the gun is opened, the cocking slide will project under the nose of each of the hammers and as the barrel is swung downwardly, the nose of the hammers will be forced upwardly to thus cause the two sears to engage the respective 100 firing notches of the hammers.

Now as may be seen in Fig. 2, the little nose 105 31' of the dog fits within the recess 21 in the little follower 20, and likewise the far hammer will have its dog fitting within the follower of its cocking spring.

Of course, there will be a sear spring 36 for each of the sears so that they will always 110 immediately engage the firing notches of the respective hammers when the gun is broken to be cocked.

These sears in a double barrel gun, (as shown in Fig. 4), extend rearwardly and 115 then inwardly as at 37 to be engaged or operated by the respective triggers.

Now the operation of the rebounding hammers (and describing the action of one) is 120 as follows:

Considering that the gun has been fired, the hammer 12 will now be in the position as shown in Fig. 1. To cock the gun, the lever 6 will be released in the ordinary way, and the barrel moved downwardly to the 125 position shown in Fig. 2. The cocking slide will be forced rearwardly a slight distance under the nose 30 of the hammer, as may be seen in dotted lines in Fig. 2, and as the barrel is swung on the pivot 9, it will force 130

the hammer to the position shown in Fig. 2, the cocking spring, of course, through the follower, bearing hard against the nose 31' of the dog 31. The nose of the sear will then engage the firing notch of the hammer, as may also be seen in Fig. 2. Now when the gun is closed, the hammer will remain in the position as shown in Fig. 2, but of course the cocking slide will again retract to its normal position.

Now when the trigger 17 is manipulated, the hammer spring bearing against the dog 31 of the hammer, substantially shown in Fig. 1, will cause the hammer (upper portion) to fly forwardly and the nose 23 will pass through the plunger hole 22 to strike the primer of the cartridge. The dog 31 will have its rear portion strike against the hammer just above pivot pin 13, and the pressure of the hammer spring bearing against the nose of the dog mounted in the hammer, and the dog in turn striking against the hammer just above the pin 13 will cause the hammer to rebound from the position shown in the dotted lines in Fig. 1 to the position shown in full lines, thus preventing the nose 23 from remaining in a protruded position through the plunger hole.

Thus, it will be seen that the cut-out portion 34 bears against the pin 13 after the hammer has been fired which, in a manner, limits the forward movement of the hammer, while on the firing, the upper end 34' of the dog will contact with the hammer just below the firing pin to cause a slight rebound, as clearly shown in Fig. 1. In other words, the pointed nose 34' extends over the pivotal pin for a sufficient distance to strike the hammer and to thus cause a slight rebound of the same.

Therefore, when the lever 6 is moved and the gun is to be opened, there is no possibility of the nose 23 of the hammer still projecting within the primer, thus assuring at all times that the gun may be quickly broken to eject the old shell or shells and cock the gun to receive new ones.

It will also be seen that there is no danger of the striking pin or nose of the hammer being protruded as the gun is closed, which heretofore has often caused the firing of the shell during the closing action of the gun.

It will also be seen that this rebounding hammer mechanism is suitable for either a single barrel gun with the one hammer, or a double barrel gun with the two hammers, and I have illustrated the double barrel gun just to show the arrangement and nesting of the hammers and sears.

From the foregoing, it will be seen that I have provided a gun with a rebounding hammer, wherein the hammer spring is utilized not only for the driving action of the hammer, but also for the rebounding action of the hammer, so that it is a simple matter

to construct or add the improvement outlined to certain types of guns now in use, it being only necessary to change the construction of the hammer and add the little dog and follower.

It will also be seen that there is no possibility of the firing pin or striking nose of the hammer to ever project beyond the outer surface of the plunger hole, as the hammer spring pressing against the dog even after the hammer has been fired, will cause the hammer to be kept in a rebounded position.

Guns formed in this manner have given excellent and constant service, it never having been necessary to open the gun across the knee, or to exert great pressure on the same, as it is impossible for the firing pin to remain protruded within the primer of the shell. Likewise, it is not possible to prematurely fire the shell during the closing of the gun.

Having thus described my invention, what I claim as new and desire to secure by Letters Patent is:

1. A shot gun comprising in part a frame, a hammer having an integral firing nose thereon, said hammer pivotally mounted in said frame, a dog mounted on said hammer, a hammer spring bearing against said dog, a sear for holding said hammer, means for releasing the sear, and said dog being adapted to strike against the hammer above the pivotal mount of said hammer when said hammer is released, to thereby cause the hammer to slightly rebound.

2. A shot gun comprising in part a frame, having a plunger opening therein, a hammer pivotally mounted in said frame and the nose of the hammer adapted to pass through said plunger opening when the hammer is released, a dog on the forward end of said hammer, a hammer spring bearing against said dog, means for cocking the hammer, a sear for holding the hammer, and the dog adapted to contact with the hammer just above the pivotal point of the hammer when the hammer is released, to thereby cause the hammer to rebound after being released and the nose of the hammer to rest to the rear of the front face of the plunger opening.

3. A shot gun comprising a frame having a plunger opening therein, a pivotally mounted hammer in the frame, and the striking nose of the hammer adapted to pass through the plunger opening when the hammer is released, means pivotally carried by the hammer, a hammer spring engaging said means, and said means having a nose to contact with said hammer so that on a release of the hammer the striking nose of said hammer will protrude through the plunger opening and immediately rebound to a position slightly behind the face of the plunger opening.

4. A rebounding hammer mechanism for shot guns, comprising a pivotally mounted

hammer in said frame, the frame having a plate with a plunger opening therein, said hammer provided with a striking nose adapted to pass through said opening when the hammer is released, a pivotally mounted dog carried by said hammer, and the dog adapted to bear against said hammer when the hammer is released, a hammer spring bearing against said dog to provide the driving means for the hammer and to also provide the rebounding action for said hammer.

5 5. A rebounding hammer mechanism for shot guns, comprising a frame having a plate with a plunger opening therein, a pivotally mounted hammer having a striking nose adapted to pass through the said plunger opening, a hammer spring and means on the lower end of the hammer engaging said spring and to abut against said hammer so that when the hammer is released, the hammer spring will cause the striking nose of the hammer to pass through said plunger hole, and also cause the hammer to rebound so that the striking nose of the hammer will normally rest behind the face of the plunger opening.

10 6. A rebounding hammer mechanism for shot guns comprising a pivotal hammer with a striking nose, a dog pivotally mounted on said hammer, a hammer spring bearing at all times against said pivotal dog and the said dog adapted to contact with the hammer and the pivotal means of said hammer when the hammer is released to thereby cause a rebounding action of the hammer and to cause the striking nose of the hammer to rest at a point to the rear of its striking position.

15 7. A rebounding hammer mechanism for shot guns, comprising a pivotal hammer having an integral firing nose, a hammer spring, a pivotal dog carried by the hammer and having a part in engagement with said hammer spring, the dog normally out of engagement with the pivot of the hammer and the front wall of the hammer adapted to strike an upper portion of the dog when the hammer is released whereby the hammer will rebound to a position slightly to the rear of its striking position.

20 8. A rebounding hammer mechanism for shot guns, comprising a cocking slide-engaging portion and a striking portion, and said hammer provided with a pivotal opening near the merging line of these two portions, an irregularly-shaped dog pivotally mounted at a point below the said opening and slightly in front thereof, a spring engaging a portion of said dog, and the rear upper portion of said dog adapted to strike the hammer when the hammer has moved to its forwardmost position to cause a slight rebound of the same.

25 9. A rebounding hammer for shot guns comprising an upper portion with an integral striking nose, an outwardly extending portion adapted to be engaged by a cocking slide,

said hammer provided with an opening to receive a pivot pin, the upper part of the hammer being offset with relation to the outwardly extending portion, said offset portion being slotted to receive a pivoted dog and the rear of the dog being slightly cut away and the hammer adapted to strike an upper portion of the dog when the hammer is released whereby the hammer will rebound to a position slightly to the rear of its striking position.

30 10. A rebounding hammer for shot guns comprising an upper portion with an integral striking nose, an outwardly extending portion adapted to be engaged by a cocking slide, the upper part of the hammer being offset with relation to the outwardly extending portion, a dog pivoted to the outwardly extending portion of the hammer and the said dog provided with a nose adapted to engage a hammer spring, and the dog being limited in its rearward movement to thus substantially become a solid part of said hammer.

35 11. A rebounding hammer for shot guns comprising an upper portion having a striking nose thereon, an outwardly extending portion adapted to contact with a cocking slide, and this last mentioned portion provided with a slot, an irregular shaped dog pivotally mounted in the slot and its nose adapted to engage a cocking spring, and its rear adapted to engage at times a forward wall of the hammer to thereby cause a rebounding action when said hammer is released.

40 12. In a double barrel shot gun a pair of independently operable pivotal hammers, a cocking slide for setting said hammers when said gun is open, independent sears for holding said hammers in their cocked position, each of said hammers provided with an integral firing nose and a dog, a cocking spring for each of said hammers and engaging said respective dogs and the dogs respectively limited in their rearward movement by the pivotal pin for the hammers, and the rear upper portions of the respective dogs contacting with the respective front faces of the hammers, whereby the hammer springs will cause their respective hammers to rebound slightly from their striking position when they are released.

45 13. In a double barrel shot gun a pair of hammers each provided with a respective integral striking nose pivotal means for supporting the hammers, means for cocking said hammers, sears for holding said hammers in cocked position, a trigger mechanism for releasing said sears, each of said hammers provided with a pivotally mounted dog, hammer springs respectively engaging said dog and the respective dogs being limited in their rearward movement by the pivotal supporting means of the hammers and the rear upper walls of the dogs whereby the hammers will rebound slightly from their foremost strik-

ing position, when the respective triggers are operated.

14. In a double barrel shot gun a pair of hammers, each provided with a striking nose, a pivotal pin for supporting both of said hammers, a cocking slide for cocking said hammers, sears for holding said hammers in cocked position and trigger mechanism for releasing said sears, each of said hammers carrying a pivotally mounted dog, hammer springs respectively engaging said dog, and the respective dogs being limited in their rearward movement by the pivotal pin supporting the hammers, the hammer springs respectively driving the hammers when the triggers are operated and the rear upper portions of the dogs contacting with their respective hammers causing the respective striking noses to rebound slightly from their foremost striking position.

In testimony whereof I affix my signature.
